DESIGN FOR A SHAVING BOWL OR THE LIKE

Frank McIntosh, New York, N. Y.

Application January 6, 1942, Serial No. 105,039

Term of patent 3½ years

To all whom it may concern:

Be it known that I, Frank McIntosh, a citizen of the United States, residing at New York city, in the county of New York and State of New York, have invented a new, original, and ornamental Design for a Shaving Bowl or the like, of which the following is a specification, reference being had to the accompanying drawing, forming part thereof.

Fig. 1 is a top plan view of a shaving bowl or the like embodying my new design;

Fig. 2 is a front elevational view; and

Fig. 3 is a rear elevational view thereof.

I claim:

The ornamental design for a shaving bowl or the like, substantially as shown.

FRANK McINTOSH.
